FAN

Cecil Poff, Tulia, Tex.

Application April 17, 1942, Serial No. 439,413

4 Claims. (Cl. 230—274)

My invention relates to air circulation, and has among its objects and advantages the provision of an improved fan embodying fan units so constructed and arranged as to cause impingement of two oppositely flowing air streams to laterally deflect an air stream radially in all directions from the zone of impingement of the two air streams.

In the accompanying drawings:

Figure 1 is an elevational view with certain parts broken away for the purpose of illustration;

Figure 2 is a sectional detail view of a bearing;

Figure 3 is a sectional detail view of another bearing;

Figure 4 is a view taken from the position indicated by line 4—4 of Figure 1;

Figure 5 is a sectional view of an air venting conduit for the fan motor;

Figure 6 is an elevational view of the fan structure;

Figure 7 is a top plan view of the fan structure;

Figure 8 is a fragmentary view of a frame member; and

Figure 9 is a fragmentary view of a frame arm coacting with the frame member of Figure 8.

In the embodiment selected for illustration, I make use of a base 10 which comprises a housing for a motor 12 mounted on the bottom 14 of the housing. This bottom is perforated, as at 16, for the inlet of air to the housing. The motor shaft 18 extends vertically through a tubular neck 20 extending upwardly from the housing cover 22. Upon the neck 20 is mounted the fan structure 24.

Referring to Figures 6 and 7, fan units 26 and 28 are mounted on the vertical shaft 18. The units 26 and 28 are spaced vertically one from the other and the blades 30 and 32 of the units 26 and 28, respectively, are interconnected at their ends by vertical blades 34. Bodies 36 fixedly secure the inner ends of the respective blades 30 and 32 to the shaft 18.

While the fan units 26 and 28 are fixedly secured to the shaft 18 for rotation therewith as a unit, the blades 30 are of reversed twist with respect to the blades 32 so that the fan unit 26 directs an air stream upwardly axially of the shaft 18 while the fan unit 28 directs an air stream downwardly axially of the shaft. Head-on impingement of the oppositely moving air streams one with the other creates a horizontal air stream flowing radially from the axis of the shaft 18 in all directions. A supplemental lateral deflection of the horizontal air stream is secured by reason of the two blades 34, which blades

are so tangentially arranged with respect to the circle described by the rotating fan assembly as to assist in the lateral deflection of the air radially in all directions.

An ornamental and protective frame structure 38 encloses the two fan units. This frame structure comprises vertical bars 40 having tenons 42 at their ends receivable in slots 44 in radial arms 46 and 48. Arms 46 are secured at their inner ends to a hub 50 secured to the upper end of the neck 20 while the inner ends of the arms 48 are secured to a hub 52. Figure 4 illustrates the inner ends of the arms 48 as being provided with tenons 54 secured within slots 56 in the hub 52. The arms 46 are secured to the hub 50 in the same manner. A thrust bearing 58 is mounted in the hub 50 for supporting the shaft 18 and a self-aligning bearing 60 is mounted in the hub 52 for supporting the upper end of the shaft 18.

Figures 8 and 9 illustrate the end construction of one bar 40 and one of the arms 48. All the bars and arms 46 and 48 are similarly constructed at their ends. In Figure 9, the arm 48 includes a depending finger 62 having its slot 44 extending inwardly from its lower end. A notch 64 is provided in the bar 48 adjacent the finger 62, and the finger is provided with an opening 66 registering with an opening 68 in the tenon 42 of the bar 40, so that the bar and the arm may be fixedly secured through the medium of a rivet 70, as illustrated in Figures 1 and 4. A notch 72 is provided in the inner edge of the bar 40 of Figure 8.

Two bands 74 are placed in the respective notches 64 and 72 at the upper and lower ends of the bars 40, as illustrated in Figure 1, which bands engage peripherally with the finger 62 and the bars 40 and are restrained from relative axial movement by reason of being housed in the notches. Wire bands 76 are spaced vertically of the shaft 18 and are held in place by notches 78 in the outer edges of the vertical bars 40. Thus the wire bands 76 are restrained from relative movement axially of the bars 40, and the bands are preferably grouped at the lower and upper ends of the frame structure for ornamental purposes, in addition to functioning as structural members in the frame structure 38.

The arms 46 and 48 are so spaced as to permit free circulation of air therebetween. A carrying handle 80 is secured to the hub 52. Upon the shaft 18 inside the housing 10 is secured a fan 82 which draws air through the perforations 16 for motor cooling purposes. The air is evacuated

through the tubular neck 29 and slots 84 in the hub 50.

The reversed screw or twist of the fan units 26 and 28 balance end thrust on the drive shaft 18 since each fan reacts against the other.

The bands 74 lie in the respective planes of the two fan units 26 and 28 to afford good protection against injury from the blades.

Without further elaboration, the foregoing will so fully illustrate my invention, that others may, by applying current knowledge, readily adapt the same for use under various conditions of service.

I claim:

1. An air circulating fan comprising a vertical drive shaft, vertically spaced fan units fixedly connected with said drive shaft, said fan units being of reverse screw formation to cause impingement of two oppositely flowing air streams axially of said shaft to cause an air stream to flow radially from the axis of the shaft in all directions, a base, a motor mounted on said base and operatively connected with said drive shaft, a protective frame mounted on said base and enclosing said fan units, said protective frame comprising vertical bars spaced circumferentially about said fan units, upper and lower arms arranged radially with respect to the axis of the drive shaft, interconnected one with the other at their inner ends and with the respective upper and lower ends of said vertical bars, bands extending circumferentially about the respective

planes of said fan units, shoulders formed on the vertical bars and said radial arms for supporting said bands, and circular elements extending circumferentially about the assembled vertical bars.

5 2. The invention described in claim 1 wherein said radial arms are interconnected at their inner ends by hubs and in which said hubs are provided with bearings for supporting the drive shaft.

10 3. The invention described in claim 1 wherein said base comprises a housing having a tubular neck supporting said protective frame, in which said housing is provided with a motor operatively connected with said drive shaft, and in which said tubular neck is provided with air venting openings and the housing is provided with an air circulating fan fixed to said drive shaft.

4. An air circulating fan comprising a vertical drive shaft, fan means mounted on said vertical drive shaft, a base, a protective frame mounted on said base and enclosing said fan means, said protective frame comprising two vertically spaced hubs, arms fixed to said hubs and radiating from said shaft, vertical rods connected 25 at their ends with the respective arms, said rods and said arms being notched, circular bands lying in said notches and having peripheral engagement with said rods and said arms, and endless elements encircling said rods.

30 CECIL POFF.
